UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

1,407,182.

Specification of Letters Patent. Patented Feb. 21, 1922.

Application filed March 30, 1914. Serial No. 828,252.

To all whom it may concern:

Be it known that I, ERASTUS E. WINKLEY, a citizen of the United States, residing at Lynn, in the county of Essex and State 5 of Massachusetts, have invented certain new and useful Improvements in Heel-Building Machines; and I do hereby declare the following to be a full, clear, and exact description of the invention, such as will enable others 10 skilled in the art to which it appertains to make and use the same.

This invention relates to machines for assembling blanks, such as heel lifts and more particularly to such machines for automatically 15 selecting a graded series of blanks from their sources of supply and assembling them into a heel pile from which a heel blank is produced.

The object of the invention is to improve 20 the construction and operation of automatic machines of the character described.

In accordance with this object one feature of the invention contemplates the provision of a series of magazines each adapted 25 to contain a stack of blanks appropriate for use in building any desired type of heel, and means in cooperative relation with the magazines while each magazine retains its quota 30 of stacked blanks, and effective to produce from all, or any predetermined number, of said magazines, a series of said blanks suitable for a heel pile of the character required.

Another feature of the invention provides 35 a mechanism including a series of magazines, together with means adapted automatically to produce from said magazines a multiplicity of blanks suitable for building a single heel and thereafter to bring said 40 blanks into a proper superimposed relation such that when secured permanently together they will form a heel pile of the desired contour.

In one of its aspects, the invention contemplates the use of feeding or delivering 45 means effective to place a series of adhesively coated blanks such as heel-lifts, upon a support comprising a series of discontinuous surfaces arranged in stepped relation, by 50 means of which they may readily be collected in superimposed relation. In the preferred form of the invention the discontinuous supports, which normally hold the

lifts in correspondingly disposed positions 55 form a row of lift-receiving seats and are movable in the line of the row one over the other, to collect the lifts in superimposed relation.

Any convenient mechanism may be employed to supply heel-lifts to the supports 60 the preferred arrangement being a row of magazines arranged opposite thereto, with means for transferring lifts therefrom simultaneously to said supports. This form of the invention, in its broader aspects, comprises means for producing a series of heel lifts from a series of magazines and depositing them in dispersed relation, from whence they are collected into a stack at a common point. In the preferred construction 65 the lift-receiving seats are at the ends of arms, all pivoted at one end at a common center, which are collapsed fan-wise to collect the lifts in a stack.

Another feature contemplates the provision of mechanism, in a machine comprising a series of magazines, which will feed the blanks in each magazine independently 70 of the other magazines, and yet all simultaneously in point of general effect, but which will automatically cease operations 75 throughout when the supply of blanks in any one of the magazines becomes exhausted, or nearly exhausted.

Another feature provides for a blank 85 feeding mechanism which will be effective to regulate the feed of the blanks contained in a magazine and in which the rate of feed will be controlled entirely in accordance 90 with the rate at which the blanks are removed and which will automatically compensate the rate of feed to meet variations in the thickness and compressibility of the blanks.

Another feature contemplates the provision 95 of means for feeding a stack of blanks in cooperative relation with a device for picking the uppermost blank periodically from the stack, and to combine this mechanism with means for frictionally binding the 100 edges of the uppermost blanks during non-feeding or removing periods to prevent a loss of control over the stack.

Another feature contemplates the provision 105 of an instrumentality adapted to receive and individually grip a series of blanks

in dispersed relation, then to bring said blanks into superimposed registry and then to release the grip on each of said blanks to permit them to be pressed together flatwise to form a heel pile.

Another feature provides a stacking instrumentalities for blanks that will bring the same into superimposed position and proper marginal registry at a common point in combination with means which will then press said blanks together flatwise to secure them together by adhesive material.

Under this aspect of the invention the pressing instrumentalities comprise an anvil and an opposed pressure member, forming a heel-holder, between which the blanks are stacked when assembled together, whereupon the pressure member is operated and the blanks are finally fastened together while under pressure.

Other objects and features of the invention will be in part obvious from the annexed drawings and in part indicated in connection therewith by the following analysis. The invention accordingly comprises the features and combinations of parts having the unique relations of the members and relative proportioning and disposition thereof; all as hereinafter described and then particularly pointed out in the appended claims.

The preferred form of the invention is illustrated in the accompanying drawings, in which:—

35 Fig. 1 is an elevation of the left side of the machine showing a general assembly thereof. Figs. 2 and 3 are enlarged upper and lower sections of Fig. 1 also in side elevation, but with portions of the frame omitted and with various parts broken away to show more clearly the details of construction. Fig. 4 is a rear elevation of the upper section, as portrayed by Fig. 2, looking in the direction of the arrow "Fig. 4". Fig. 5
40 is a rear elevation of the lower section of the machine, as portrayed by Fig. 3 and looking in the direction of the arrow "Fig. 5" thereof. Fig. 6 is a top plan of the machine, as portrayed by Fig. 1, looking in the direction of the arrow "Fig. 6" thereof. Fig. 7, is a plan of the lower deck of the machine, on the line 7—7 as portrayed by Fig. 2, looking in the direction of the arrow "Fig. 7" thereof. Fig. 8 is a plan of
45 the lower deck of the machine showing the fan spread out to receive the dispersed blanks preparatory to bringing the same into superimposed registry. Fig. 9 is an enlarged detail of the operating head for the blank picker together with the mechanism for causing it to release its blank at the proper time. Fig. 10 is an enlarged plan showing the details of the mechanism for spreading and closing the fan and for the laterally ejecting of the heel formed of the

blanks superimposed by said fan. Fig. 11 is an enlarged side elevation of Fig. 10 showing further details thereof and Fig. 12 is a detail of the release catch which permits the automatic return of the registering device 70 after it has performed its functions. Fig. 13 is an enlarged fragmentary side elevation showing the lever mechanism for driving the nailer and showing the toggle system for withdrawing the anvil to permit of the 75 discharge of the heel. Fig. 14 is a fragmentary horizontal section taken through line 14—14 of Fig. 13. Fig. 15 is an enlarged fragmentary rear elevation showing the stack compressor, the silent ratchet therefor, and the means for spreading the blades to release the superimposed blanks when they are being compressed together stack-like. Fig. 16 is a side elevation of Fig. 15. Fig. 17 is a horizontal section taken through line 17—17 of Fig. 21, showing the hand-lever arrangement for enabling each elevator or feeding-finger to drop to the bottom of its mechanism to enable the supply of blanks to be replenished therein, and also showing 80 a detail of the automatic stop and a detail of the feed regulator. Fig. 18 is an enlarged fragmentary detail showing the constantly reciprocating slotted member and the pin in the rack-shaft whereby said shaft 95 will be intermittently operated when said pin registers with the slot. Fig. 19 is a left side elevation, partly in section, of the delivery end of the magazine showing the finger that determines the rate of feed of 100 the blanks by cooperation with the uppermost blank of the stack. Fig. 20 is a view looking in the direction of the arrow "Fig. 20" on Fig. 19. Fig. 21 is an enlarged fragmentary side elevation showing the details of the blank feeding mechanism, as well as those of the automatic stop. Fig. 22 is a view of the parts portrayed by Fig. 21 looking in the direction of the arrow "Fig. 22" thereof. Fig. 23 is a plan of two empty 110 magazines taken transversely through the guide rods thereof to show the arrangement of the elevating finger. Figure 24 is a fragmentary side elevation of the parts portrayed by Fig. 23. Figs. 25, 26 and 27 show 115 various positions of the blank picker and of the means for frictionally gripping the upper blanks of the stack.

Referring to the embodiment of the invention illustrated in the drawings and continuing by way of a more detailed description of this embodiment, the various major sub-mechanisms will be described in about the order in which they take part in the various manipulations of a heel lift, or other blank used for a like purpose, in the machine, thereby affording a better grasp of the general scheme of the organization.

The hand control for starting and stopping includes the lever K (Figs. 1, 3, 5 and 130

7) extending upwardly from the base 1 of the machine at the left side thereof. This upright hand lever is pivotally supported at 2 (Fig. 5) by a bracket 3 and its lower end 5 is pivoted at 4 to a long rod 5 (Figs. 5 and 7) that extends horizontally through the base towards the right side of the machine near which it is supported by the base-bearing 6 (Fig. 5). Changes in the position of 10 this hand-actuated long rod 5 are communicated to a rearwardly extending link 7 (Figs. 3 and 7) by means of a bell-crank lever 8 pivoted directly to the link 7 and indirectly to the long rod 5 by means of a short link 9. 15 This transversely extending link 7 in turn is pivoted to the operating arm 10 of a vertical shaft 11 which is supported in bearings at the right of the center-line of the machine. Extending rearwardly from the 20 upper end of this shaft 11 is an arm 12 (Figs. 3 and 7) that terminates in a yoke 13 having anti-friction rollers 14 bearing in the annular raceway 15 of a clutch-member 16 (Figs. 5 and 6) which is splined to the main 25 driving shaft 17 and which, in the one position, frees said main shaft from the source of power, and which in its other position engages the clutch 18 of a power-driven gear 19, mounted on a sleeve 17' loose on the shaft 30 17, so that in that event the main shaft is power-driven. In this instance, the gear 19 receives motion from the main driving pulley 20, which is connected to the sleeve shaft 17', through the first-drive gear 21 and the 35 back gears 22 and 23 as shown in Fig. 5. Another loose pulley 24 may be arranged adjacent to the driving pulley 20.

It will be readily perceived from this that when the handle of lever K is thrown towards the machine, or to the left viewing 40 Fig. 5 the latter will be stopped, and conversely when pulled out, the machine will be started. The mechanism for automatically stopping the machine, whenever any magazine becomes empty, operates by turning the 45 control shaft 11 and the clutch lever 12 automatically, as will shortly be described more fully.

Whenever the main shaft 17 is driven, so 50 also will the four cam-wheels X, Y, Z and W (Fig. 5) be driven in the direction indicated by the arrows thereon, and these cam-wheels actuate the ten levers A, B, C, D, E, F, G, H, I and J, that control or effect 55 operative movement of the various major instrumentalities that manipulate the blanks.

These blanks or so-called "lifts" may all 60 be of the same size (as may be required by one type of heel) or they may be of the graduated sizes necessary for the most economical manufacture of another type of heel characterized by a strongly curved or tapered contour. This machine is well adapted for making either type of heel, as it may 65 embody as many different magazines as

there are different sizes of "lifts" composing the heel, and these magazines may be of various sizes.

The series of magazines may thus, as shown in Fig. 8, be graduated in size progressively so as to retain the blanks or "lifts" suitable for the different parts of a taper heel, and these magazines are preferably arranged in concentric relation with an operating center which may be regarded as the 75 axis of the machine.

These magazines may be formed of top and bottom U-shaped plates connected together by means of vertical rods to form a sort of cage. Thus, as shown by Fig. 23, 80 the bottom may consist of the member 25 having an opening 26 for the admission of a lifting-finger, or elevator. A series of rods or guides 27 are secured at their lower ends to this member 25 (Figs. 3, 23 and 24), and 85 their upper ends are secured to a somewhat similarly shaped flexible member 28 (Fig. 7). These various magazines, which on Fig. 7 are indicated as L, L', L'', L''', etc., are in this instance of a progressively decreased size, and they all rest on a segmental plate 29, which is supported by the collars 30 (Figs. 3 and 7) adjustably secured to the posts 31, as is shown in closer detail by Fig. 24. This construction makes for a 90 ready interchangeability of the cages as they may be replaced by others differently proportioned to meet the demands of various styles of heels.

The blank elevating mechanism includes 100 an elevator M for each magazine, shown best by Figs. 1, 3, 21, 22, 23 and 24. This consists of a sleeve 32 circumscribing a vertical rack-rod 33 that uprises adjacent each cage L. This rod 33 has no end-wise movement except for the purpose of stopping the machine. A suitably formed blank-supporting finger 34 extends laterally between the two innermost guide rods 27, through the opening 26 in plate 25, into the interior of 110 the magazine, and it supports the overlying stack of blanks therein contained. The elevator M rises at an automatically regulated rate of feed so as to keep the uppermost blank of the stack always near or directly at 115 the upper end of the magazine, so that as fast as one blank is withdrawn, another will assume its place more or less approximately. In other words, about the same level will always be maintained at the upper end of 120 the stack, but it is to be noted that the feed of this elevator M is discontinuous rather than regular, in that skips may take place in its intermittent action as will presently be described.

The means for intermittently uplifting the elevator includes a reciprocating shaft 35 (Figs. 21 and 22) that uprises parallel to the rack-rod 33. Both of these shafts or rods enter apertures in an uppermost frame 130

portion 98 (Figs. 1, 7 and 19), and while the machine is in operation the shaft 35 will at frequent periods have a short up and down reciprocation. Both of these rods may 5 be rotated about their axes and thus form rock-shafts. A pair of pawls 36 and 37 are pivoted to the elevator M, and their engaging points are preferably spaced apart a distance greater than an even multiple of the 10 tooth pitch of the rack-shaft 35, so that the one will be in tooth-engaging position when the other is riding over a tooth. Springs 38 (Figs. 21 and 22) normally urge these pawls into engagement with the teeth of the rack-shaft. Similarly a complementary pair of 15 pawls 39 and 40 are pivoted to the elevator M and through apertures 41 therein enter into engagement with the teeth of the rack-shaft 33. Springs 42, in like manner, serve 20 to maintain the engaging ends of these pawls in operative relation with these teeth in a manner similar to that already specified. From this, it will be seen that an up and down reciprocation of the rack-shaft 25 35 (which is also a rock-shaft) causes the elevator M gradually to crawl upwardly until suitably stopped.

The means for reciprocating the rack-shaft 35 includes a sleeve 43 (Figs. 18, 21, 30 and 22) having slots 44 in its upper end. This sleeve 43 loosely surrounds the rack-shaft 35, and it is constantly reciprocating up and down thereon, so that whenever the radial slots 44 are aligned with the projections 45 extending from the rack-shaft 35, then no motion will be imparted to said rack-shaft, but when said projections 45 do not register with said slots 44, then the projections 45 will be engaged by the upper 35 edge of the sleeve 43, and the rack-shaft 35 will be elevated slightly.

This constant reciprocation of the sleeve 43 is maintained by a collar 46 that loosely surrounds the sleeve 43, and which is connected by links 47 to the overlying end of a rock-lever 48 (Fig. 3) that is pivoted at an intermediate point 49 to a suitable standard 50 rising from the base, and at its other end, the rock lever 48 terminates in a rounded end 51 entering the annular groove 52 of a common reciprocator 53. This reciprocator slides up and down on a shaft 54 uprising from the base of the machine, preferably in concentric relation with the several 55 magazines, as it is used to actuate the elevators M for all of them, and it is pivotally connected to the arm 55 of an operating lever A by means of a suitable link 57 (dotted lines in Fig. 3). This operating lever is 60 pivoted at 58, and, at its upper end, carries a roller 59 that normally rides on the bottom of a cam surface X^a (Fig. 3) on the periphery of the camwheel X. At one point on its periphery, this cam-surface X^a provides an offset portion 62, that produces a

periodic oscillation of the lever A, and the parts connected therewith.

The foregoing description, although given especially with reference to a single magazine L, applies equally to all of them, because they are all connected with the common reciprocator 53 in the same manner as with the magazine L, and the parts are merely duplicated, and, of course, the elements 53, 55, A, 59, etc., are all common to each of the magazines.

The automatic stop for the blank feed is for the purpose of discontinuing the operation of the machine whenever anyone of the magazines becomes nearly exhausted. This automatic action takes place whenever one of the stack elevators M impacts a pin or stop 63 (Fig. 19) projecting from the upper end of the rack-shaft 33. The effect of such impact is to uplight the entire rack-shaft 33, moving it in an axial direction, and this, through certain intervening mechanism, throws the control shaft 11 in the same direction that it is turned by pulling out the hand lever K (already described) to stop the machine.

Referring to Figs. 17 and 21, it will be noted that the rack-shaft 33 has secured to its lower end a collar 64, as well as an operating handle 65 and a gear segment 66. Normally resting on the collar 64 is a part 67 secured to the lower end of a link 68 (see also Fig. 3), and, projecting from the other side of this lower link end, is a pin 69 that is guided by a slot 70 in a bracket 71 rising from the machine frame. The upper end of the link 68 is in turn pivoted to a rock lever 72 (Fig. 3), fulcrumed in the bracket 50, that is normally urged by means of a contractile spring 73 in the direction 100 needed to keep the part 67 on the collar 64. The other end of this lever enters between the cheeks 74 and 75 of a second common actuator 76, which controls the mechanism that renders operative an automatic stop 105 instrumentality.

The levers and parts thus far described will be duplicated for each of the different magazines and, as will be perceived, slots 70 of the guide 71 enable any one of the magazine feeding mechanism to produce a shifting of the common actuator 76 without interference from any of the others. A relatively slight force will suffice to actuate these parts. When the common actuator 76 is depressed 110 by an uplifting of the right hand end lever of the rock 72, the bell crank lever 77 will turn clockwise (as viewed by Fig. 3) producing a corresponding swing of the lever 78, through the agency of the resilient connection 79 which (as shown by dotted lines in Fig. 3) consists of a rod 80 having its head 81 telescoped by a sleeve 82, and held in contractile relation by an expansile spring 83. The purpose of this connection is to provide 115

resiliency in what otherwise would be a positive connection so that breakage may not occur through the positive effect of the cam. This lever 78 is pivoted at 84 to a rock 5 sleeve 85 that is mounted on an upright pivot pin 85' positioned by the bracket 86 so that when the lever 78 is uplifted, the roller 87 on its end will be brought into the path of the cam dog X^b (Figs. 3 and 5) on 10 the periphery of the cam disc X, which will deflect the lever laterally at the impact, thus swinging the sleeve 85 and moving the arm 89 carried by said sleeve to the right into the position shown by Fig. 5. This moves 15 the link 90 (Figs. 5 and 7) similarly and, through the arm 91, turns the control shaft 11 contra-clockwise and throws out the clutch 16, thus stopping the machine.

The means for returning the elevator M 20 to its initial position depends upon the principle that when both the rack-shafts 33 and 35 are rotated sufficiently, all pawls will be disengaged and the elevator can drop of its own weight. This simultaneous rotation 25 may be effected automatically, as well as by hand.

Referring to Fig. 17, it will be noted that the hand lever 65 is integral with the gear 66, and the latter meshes with a gear 92 30 fast to the rack-shaft 35, so that when the handle is swung, not only will the rack-shaft 33 be rotated, but also the other rack-shaft 35, and the elevator pawls will be consequently wholly disengaged, and the elevator will drop. The same effect may be obtained automatically by means of the pin 63 35 (Fig. 19) and the cam 93 (Fig. 22) carried by the upper end of the elevator sleeve. When this cam impacts this pin, it will cause 40 the shaft 33 to rotate the same as when turned by hand, and with the same effect.

The automatic feed regulator for the elevator is for the purpose of rendering the feed operative or inoperative as the case may be 45 in accordance with the level reached by the uppermost blank of the stack.

Referring to Figs. 19 and 20, 94 designates the uppermost blank, and against the edge of this blank presses a finger 95 extending from the sleeve 96, which is journaled on a pin in the block 97 secured to the adjacent frame portion 98. A second arm 99 depends from this sleeve and a spring 100 urges the finger into the path of 50 the edge of the uppermost blank so that when the uppermost level is unoccupied, this finger will swing towards the right, (viewing Fig. 19), and the arm 99 towards the left. This motion is utilized for rendering effective the blank feed mechanism 55 as will now be described. This element will hereinafter be known as the feed controller N, since it is the means for determining the rate of feed for the blanks. The instrumentality through which this feed con-

troller is effective is here constructed as follows:

A rock-shaft 101 (Figs. 1, 17, 19 and 20) has its upper end journaled in the portion 98 of the middle deck of the frame of the machine and it extends downwardly to a similar bearing in the base 1. The construction is such that when this shaft is rocked into a certain position, the intermittently-acting means for propelling the blank elevator M will be rendered operative for that purpose. This is the position taken by the rock-shaft when the blank magazines are empty and it is constantly urged into this position by the spring 100. This is done through a link and lever system, extending from the lower end of the arm 99 to the rock-shaft 101, as shown best by Figs. 19 and 20. This system consists of a part or cross-piece 102 pivoted about a vertical 85 pin in the arm 99, and a similar part 103 pivoted about a horizontal stud 104 projecting rigidly from a collar 104' secured to the rock-shaft 101. A link 105 terminates at each end in a yoke or fork, each of which 90 is in turn pivoted to the adjacent part 102 and 103.

By this means, when the finger 95 of the feed controller N moves to the right (Fig. 19) by reason of a withdrawal of the uppermost blank 94, the rock-shaft 101 will turn in the direction indicated by the arrow a in Fig. 19, the effect of which will be to render effective the means for producing an elevation of the elevator M, as will now be 100 explained.

Keyed to the lower end of the rock-shaft 101 is a casting 106 (Figs. 17, 21 and 22), the lower end of which rests upon a gear-segment 107, which is freely pivoted so as 105 to permit of movement in one direction independently of the rock-shaft 101 for the purpose of avoiding breakage; and yet which is spring pressed to said shaft to give it control over the gear-segment. This gear-segment 107 has an ear 108 through which passes a rod 109, which is pivoted to a lug 110 (see Fig. 17) extending radially from the casting 106. An expansile spring 111 intervenes between the ear 108 and the end 115 of the rod 109 and it has the effect of constantly urging together the ear 108 and the lug 110, so that when the casting 106 is moved in the direction of the arrow a (Fig. 19) by the rock-shaft to which it is pinned, the gear-segment 107 will be positively moved in the same direction. This spring also provides for lost motion in case the parts are urged in an opposite direction; thus avoiding breakage under certain conditions. 120 The gear-segment 107 meshes with a gear 112 (Fig. 22) which is keyed to a sleeve 113 extending integrally from the part 43 already described. This sleeve is best seen in section, Fig. 17 and dotted lines Figs. 18 130

and 22. In consequence of this arrangement, the rotation aforesaid in the direction of the arrow *a* (Fig. 19) of the rock-shaft 101 will turn the constantly reciprocating part 43 and bring the slots 44 thereof out of registry with the pin 45, so that each time the part 43 is reciprocated by the collar 46, the rack-shaft 35 will also be reciprocated.

These reciprocations of the rack-shaft 35 will continue and the blanks will be fed upwardly in the magazine until the top blank impacts the finger 95 of the controller *N* and moves it into the position shown in Fig. 19. Thereupon, the parts above described will all take the positions shown in Figs. 21 and 22 and the feeding will at once discontinue by reason of the fact that pin 45 will now register with the slots in the part 43 and the reciprocations of the part 43 will, therefore, be ineffective to move the rack-shaft 35. The elevator will accordingly remain stationary until the cycle again repeats itself through the removal of the uppermost blank from the stack in the magazine.

25 The blank picker "O" for removing the uppermost blank is in the nature of a plunger-like device that first moves into end-wise contact with the uppermost blank of the stack and then seizes and transports 30 the same to a point where adhesive is applied, and finally carries it to and discharges it into the possession of a mechanism for assembling all of the blanks. This particular element consists of an outer tubular sleeve 35 114 and an inner actuating rod 115 (Figs. 2 and 9), but its specific construction need not be further described as it is fully disclosed in my Letters Patent of the United States No. 1,286,472, dated December 3, 1918.

40 It may be here explained, however, that when the upper end of the outer sleeve 114 is separated somewhat from the part 149, as shown by Fig. 9, certain piercing or blank retaining points pinned in the lower end of 45 the sleeve are housed within the sleeve 114 so that the lower end of the sleeve may be brought to bear flush against the surface of the blank, and then when the rod 115 follows down further into the sleeve 114, these 50 points will emerge to pierce the surface of the blank and retain it against the lower end of the sleeve as long as the parts are in this relation. The mechanism for performing this work and determining the action of the 55 blank remover or picker, as well as its position, will now be described. It will be convenient first to describe the means for determining the lateral position of the picker *O*.

The locator for the blank picker includes a 60 carriage *P* (Fig. 2) which consists of an elongated sleeve 116 adapted to slide horizontally on a rod 117 that extends radially from the central frame portion 118. This sleeve 116 is provided with a second vertical 65 sleeve 119 extending transversely thereto and

this vertical sleeve forms a bearing for the vertically shiftable picker *O* so that by horizontally shifting the position of the carriage radially with respect to the central axis of the machine, so also will the picker 70 *O* be similarly shifted. This shift may conveniently be effected by the following mechanism:

A lug 120 (Fig. 2) rises from each end of the sleeve 116 and supports an intervening 75 slide rod 121, on which slides a block 122 which is normally maintained in a central relation with the sleeve 116 by means of opposing expansile springs 123; coiled about the rod 121 on each side of the block 122. 80 To this block is pivoted one end of link 124 and its other end is pivoted to the depending arm 125 of a bell-crank lever which rocks about the fixed pivot 126 of a bracket 127 depending from the upper deck 128 of 85 the machine. The other arm 129 of the said bell-crank lever is connected by a link 130 with a common actuator 131 which has a sleeve 132 surrounding a vertical fixed rod 133, seated in a bracket 133' (Figs. 2 and 4) 90 rising from the intermediate deck 139, so as to be movable up and down thereon. It is to be understood that this common actuator 131 is connected in a similar manner to each one of a series of bell-crank levers; each 95 operating its own individual carriage *P* in the way above described. The connection between the link 130 and the actuator 131 is disconnectable as shown for a purpose to be explained later.

100 This common actuator 131 derives motion from a forwardly extending lever 134 (Fig. 2), to which it is connected by depending links 135, and this lever has a fixed pivot at 136 on the frame and, at an intermediate 105 point at 137, it is also pivoted to an elongated actuating link 138 that extends downwardly through the intermediate deck 139 of the machine. The lower end of this link 138 is in turn connected with the forward 110 end of the cam-actuated lever *D* which has its rearwardly extending arm 141 (Fig. 5) provided with a roller 142 (see Fig. 3) that is engaged by the cam-groove *X*^a in the face of the cam-wheel *X* (see Fig. 5) which 115 periodically shifts the position of the carriage *P* one way or the other, as the case may be, in correspondence with the duty to be performed by the picker *O*.

120 The actuating mechanism for the blank picker is designed so as to project the blank picker downwardly into contact with the uppermost blank; then to operate the picker points to cause them to seize or take hold of the adjacent blank; then to elevate the 125 picker to cause it to withdraw the blank from the stack (the blank vise, to be described, being temporarily released) then to hold the picker in elevated position while the above mentioned locator shifts it over a 130

5 tank of adhesive material; then to depress it to apply such material to the blank; then again to elevate the picker and hold it elevated while the locator shifts it laterally into operative relation over a blank receiving and assembling mechanism; and then to deliver the blank into the possession of the said mechanism.

10 Referring to Figs. 2 and 9, the picker actuator Q appears in this instance as a part 144 somewhat like a travelling crane and which is secured to the end of the vertically movable shaft 145 (Fig. 9) which slides in a sleeve-bearing 146 rigid with the upper 15 deck 128 of the frame of the machine. A guide rod 147 uprises from the actuator Q and has a sliding fit through the bracket 148 (Fig. 2) so that the alignment of this actuator Q is preserved. The lower surface 20 of the actuator has a horizontally elongated slot in which slides the head 149 fast to the rod 115 of the picker O. This head is retained in place by the guide rails 150 and, rigid with this head 149, is mounted a catch 25 151 (Fig. 9) which normally engages a hook 152 pivoted at 153 to the upper end of the outer sleeve 114. This hook is normally urged towards the catch 151 by the spring 154, which bears against the outer end of 30 an arm 155; which arm is utilized for the purpose of releasing the hook at appropriate intervals to permit the sleeve 114 to fall away from the head 149 and thus withdraw the picker points that hold the blank. This 35 operation will be described shortly.

This actuator Q moves up and down bodily and this motion is derived from a common actuator 151' (Fig. 2) located just over the upper deck 128 of the machine in central relation with the various elevating means for the blank picker O. This common actuator has a sleeve 152' (Fig. 4) which slides up and down on the fixed bearing shaft 153', which in turn is secured to 45 the upper deck 128 by means of the boss 154'. Said actuator has oppositely projecting lugs 155', to which are pivoted links 156 (Figs. 4 and 6) that are pivoted at their upper ends to the yoke end 157 of 50 an operating beam 158 which has its opposite end pivoted at 159 to a bracket 160 bolted at the rear of the upper deck of the machine. The common actuator 151' provides upper and lower disk-like cheeks 161 55 and 162, forming an annular channel or bearing-way 163 which receives the rounded end 164 of a walking beam R (Fig. 2) pivotally supported at its intermediate point 166 on the bracket 167. It will be perceived 60 from Fig. 6, that this beam R and this bracket 167 are typical of a plurality of similar parts arranged in radial relation with the common actuator 151'. This walking-beam R is preferably constructed to provide the resiliency in the system necessary

to avoid breakage due to any obstruction of motion of the positive actuator 151'. This may be accomplished by constructing this walking beam of two main parts or levers 165 and 168 (Figs. 2 and 6). The lever 75 indicated by 168 on Fig. 2 has a bifurcated end portion 169, which is pivoted at 166 and which receives between its cheeks the short extension 170 from its companion lever 165; which extension terminates in a stop 75 portion 171 located opposite a similar stop portion 172 rigid with the arm 168. A rod 173 is fixed to the portion 171 and loosely projects through an aperture in the portion 172 and it carries an expansile spring 174 80 which, by pressing against the portion 172 urges both together, while yet enabling them to separate or swing relatively to one another as in case motion is unduly resisted. Links 175 are pivoted at their upper ends 85 to the forked end 176 of the arm 168 and these links are pivoted at their lower ends to a boss 177 (Figs. 1 and 2) rigid with the frame Q. It will be seen that when the common actuator 151' is forced up positively, then the frame Q will be forced down 90 yieldingly by reason of the resilient rock-beam R and that all motions will be positive in the uplifting direction.

The means for oscillating the lever 158 95 includes a long link 178 (see Figs. 2 and 4) which has its upper end pivoted at 179 to the lever 158. This elongated link 178 extends straight down through the upper and lower decks 128 and 139 and its lowermost 100 end is pivoted at a point 180, just below the lower deck, to the arm 181 (Figs. 2, 3, and 5) of a lever C that rocks at an intermediate point about the shaft 182 and which has its other arm 183 extending rearwardly to one 105 side of the cam-wheel X and which carries a roller 183' (Fig. 5) in operative relation with a groove X' of the said cam-wheel. This will produce an up and down reciprocation of the common actuator 151' and will 110 hold the same for definite periods at definite planes of elevation, depending on the requirements of the head Q.

Assume the picker O to be in the position indicated by dotted lines in Fig. 2, i. e., 115 with its outer sleeve 114 lowered to a position in engagement with the uppermost blank 94 of the stack. It may be stated that the catch 152 is released in this position the parts 114 and 149 being in extended relation with the lift grasping claws of the picker withdrawn. The immediately following motion of the apparatus is a depression of the head Q which forces the shaft 115 further into the sleeve 114 and 120 this projects the claws and causes them to dig into the face of the adjacent lift. The hook 152 will then snap into engagement with its co-operating catch 151 and hold these parts in this relation during the up- 125 130

rise of the picker and until released at the end of the cycle of operations.

The picker is then elevated and carried to the right, viewing Fig. 2, over the adhesive-containing tank; but this action is carried out in a properly timed cycle with a blank-gripping arrangement which is timed to release the uppermost series of blanks in the magazine, so that the top one 10 may be freely withdrawn by the picker, but it then functions again to grip the blanks so as to prevent them from springing up by their own resiliency and compression and thus interfere with the normal operation of 15 the machine. This binding instrumentality will now be described.

The intermittently acting blank vise operates at the upper end of the stack of blanks and it regulates the freedom of feed 20 thereof so that they may not move either too freely or too stiffly, as the case may be. This instrumentality is very plainly illustrated by Figs. 2 and 7, and it consists of a push rod 184 that is pivoted at 185 to 25 a forked jaw 186 spanning the outermost upstanding rod 27 of the cage or magazine for the blanks. When this push rod is forced to the left, viewing Fig. 2, the uppermost lifts will be brought under pressure 30 of the jaw 186 and further upward movement of the stack will be resisted frictionally in proportion to the pressure applied. The movement of the rod 184 necessary for obtaining this pressure is derived 35 from a lever 187 that is pivoted at an intermediate point 188 to a bracket 189 at the outermost margin of the portion 190 of the lower deck 139 of the machine which also constitutes an annular table for the support 40 of the adhesive containing tank. The lower arm 191 of this lever is pivoted to a split collar 192, which by means of the screw 193, may be caused to clamp the rod 184 in any desired position of adjustment 45 thereof. This adjustment enables the tension to be regulated in the various magazines, as may be advisable to ensure the best operation of the machine. A second collar 194 may be carried by the rod 184 and may 50 be pivotably sustained by means of the links 196 from the part 195 secured to the under side of the table 190. The upper end of the lever 187 is pivoted to one member 197 of a toggle; its other member being the arm 198 55 of a bell-crank lever which is pivoted at 199 to the carriage P and has its other arm normally upstanding and terminating in roller 200, whereby the toggle will be broken and closed, as will be explained. The arm 60 198 of the toggle preferably has a finger 201 that extends over the companion member 197 and restrains it from swinging too far beyond the dead-center of the toggle.

The action of this toggle may be better 65 understood, by referring to Figs. 25, 26 and

27. In Fig. 25, the toggle is closed and the blank picker is in a position to deposit the blanks into the possession of a superimposing apparatus, and the upper blanks in the magazine are sufficiently free from pressure to enable them to be fed readily. The empty picker is now shifted from the center line *a—a* (Fig. 25) to the center line *b—b* and thus swings the lever 187 slightly clockwise and the blanks are now gripped so that they will not retreat under the pressure of the picker, which thereupon descends at the downward stroke of the head Q into contact with the uppermost blank. As this head 114 descends the lowermost beveled end 203 of a depending guide bar 202 secured to the picker actuator Q, is brought into contact with the roller 200 (which is somewhat in its path) and this springs the toggle tightly closed and insures 80 that the blanks are well gripped by the time the picker reaches them. After the claws are forced into the blank and the catches 151 and 152 are engaged, the head starts to rise, the picker follows it with a blank 90 and the complementary guide member 204, also secured to the picker actuator Q, rises relatively to the roller 200 until its inclined surface 205 impacts said roller, whereupon the toggle is broken, as shown by Fig. 26, 95 and the carriage P is free to travel to the right to bring the picker and blank carried by it to the center line *c—c* over the tank of adhesive 206, whereupon the parts are in the position shown by Fig. 27. The head Q now again descends and this brings the blank into the tank of adhesive as shown by dotted lines in Fig. 2, and in the meantime the frictional binding is released from the blanks in the magazine and the latter are 100 fed upwardly in accordance with the action of the mechanism heretofore described. The head Q now rises on the center line *c—c* and the carriage P now moves to the left until it is in the full line position shown 110 by Fig. 2 and again on the center line *a—a*. As the carriage travels to the left, the arm 155 of the catch strikes the side of the pawl 207 (Figs. 2 and 9) and swings it to one side about its 115 pivot 208 and against the pressure of the spring 209. These parts are carried by the releasing mechanism mounted in the stationary member 210 that depends from the upper deck 128 of the machine. Now, 120 when the head Q again descends, the pawl 207 will snap back into position over the end of the arm 155 of the catch and the means for releasing the blank into the possession of the superimposing mechanism can 125 come into play.

The fan for receiving and stacking the dispersed blanks is an arrangement whereby the blanks are received individually in their state of dispersion and are then brought 130

into superimposed registry, preparatory to being pressed together, and then nailed to bind them permanently together to form the rough heel unit or heel blank which is the product of the machine. This mechanism is shown in part by Figs. 4, 7, 8, 10 and 12 and it comprises a fixed post 240 uprising from the lower deck 139 equidistant from each of the magazines containing the piles of assorted blanks. Pivoted to this post are a plurality of blades, one for each of the magazines. These blades are all constructed alike except as to proportions, and the description of one will suffice for all.

The blade at the inner end of the series is indicated in Figs. 2, 4 and 8 by 241 and it comprises a radial flat shank, freely pivoted to the post 240 and having a U-shaped free end comprising the two blank-retaining prongs 242 and 243. The gripping edges of these prongs are contoured in correspondence with the blank that they are to retain, and they are preferably integral with the shank of the blade which is, at the point of juncture, provided with a slit 244 for the purpose of providing a slight spread of the prongs to enable them to first surround and thereafter spring in on the edges of the blank and retain it against removal or displacement. A device is provided for forcibly spreading these prongs, as will be subsequently described. A bottom plate 245 is pivoted at 246 to the prong 243 and a spring 247 urges it into the position shown by Fig. 8, and a stop pin 248 prevents it from over-swinging the said position. When this blade is swung into the proper position underneath the descending blank picker O, a spreader 249 (Fig. 2), carried by the descending head Q, enters an opening 250 (Fig. 8) provided between the prongs 242 and 243. This spreader is wedge-shaped and springs these prongs apart sufficiently to permit the blank to take position between them. The bottom plate 245 determines the initial position of the blank in true registry edgewise with the prongs. When the head Q ascends, leaving the blank behind, the wedge or spreader also ascends and permits the prongs 242 and 243 to close in on the edges of the blank and securely hold the same. In this way the several blades are filled with blanks. The means for causing the picker to release its blank when it rises will now be described.

The releaser enabling the picker to drop the blank is shown in detail in Fig. 9. When the head descends over the blade that is to receive the blank, the pawl 207 is urged by the spring 209 into vertical position so that its end is a short distance over the arm 155 operating the catch 152. Now, should the pawl carrying element move downwardly, then the pawl will impact said arm

and release the catch; thus enabling the claws to be withdrawn in the manner set forth in detail in my said Letters Patent. The carrier for the pawl consists of a push rod 212 having its lower end passing freely through a collar 213, pinned to the tubular casing 210 that is bolted to the upper deck 128 of the machine and depends therefrom, as shown. The lower end of the rod 212 carries a head 211 providing the pivot 208 for the pawl 207. At or adjacent its upper end, this rod 212 carries a collar or shoulder 216 and it is normally held in the position shown in Fig. 9 by means of the expansile spring 214 that bears at one end against the collar 213 and at its other end against the shoulder 216.

As the picker-operating head Q descends, the mechanism comes into play which resiliently urges the rod 212 downwardly with sufficient pressure to overcome the spring 214 when said rod is released under these conditions from the control of a positive-stop pawl presently to be described. This mechanism comprises a stronger spring 224 that presses at its lower end against the shoulder 216 and is held in said position by means of the stud 217 forming an extension of the rod 212. The upper end of this spring bears against a plunger 226 which in turn has its upper end contacting with an adjustable collar 230 that is mounted on a push rod 229 carried by the stationary block 228, rising from the upper deck 128.

When the picker head descends, the lever arm 168 (Fig. 2) descends and a finger 223 thereon impacts the end 231 of the plunger 229, thus forcing down the part 226 and compressing the spring 224. This would produce an immediate down-stroke in the push rod 212, were it not for the fact that a pawl 219 (Fig. 9) which is pivoted to the casing 210, provides a catch 221 that takes under the shoulder 216 by reason of the action of the spring 220, and thus prevents any movement of the push rod 212, notwithstanding the now increased pressure of the spring 224. Ultimately, however, a sleeve 225 that is rigid with the member 226 moves down until the contacting portion 218 thereof impacts the projection 222 of the pawl and throws the catch 221 to one side and, forthwith, the superior pressure of the spring 224 overcomes the weaker resistance of the spring 214 and the push rod with its now erect pawl 207 snaps down and releases the catch 152 and thus releases the blank from the picker points. These pawls 207 may be of different lengths in the case of the different magazines, to accommodate the different heights of the blades. When the head now rises, the pressure on the plunger 229 will be removed and the parts will resume their normal position under the influence of the weaker spring 214.

The fan closer.—It is to be noted that each of the blades occupies its own individual plane (see Figs. 2 and 4) and means are provided whereby, after these blades are filled, 5 they will all swing about their common center 240 and into a superimposed registry. This is done by the arm 251 (Figs. 4 and 8), which extends radially from a sleeve 252 that is loose on the post 240 and is fast 10 to its operating gear 253. At the outer extremity of this swinging arm 251 there arises a stud 254, which passes through an aperture in a part 255, secured to the uppermost blade 256 of the series. As this 15 stud 254 swings around, it successively impacts the side of each of the blades of the fan and swings them all into superimposed relation and then swings the entire set bodily over certain nailing and pressing elements. 20 A pin 251' (Figs. 7 and 8) rising from the deck 139 acts as a stop to position the blades at the nailing station.

The operating gear 253 of this arm 251 and the mechanism controlling it is shown 25 best by Figs. 8, 10 and 11. A gear-segment 257 is pivoted on a post 258 that is secured by means of the nut 259 to the lower deck 139 of the machine. This gear-segment meshes with the gear 253 and is in turn 30 operated from the arm 260 (Figs. 5 and 11) by a cam controlled lever E that is journaled loosely on a shaft 262 (Figs. 3 and 5) extending transversely of the machine. This lever has another arm 263 that extends 35 at one side of the cam wheel Y and has a roller 265 that extends laterally into a suitably formed groove Ye in said camwheel. The connection between the arm 260 of said lever and the gear-segment 257 is of a yielding or resilient nature and preferably also provides for adjustments so that the stroke 40 of the gear-segment may be varied. To that end, this connection may consist of a part 266 (Fig. 11) having a guide rod 267 on which slides a block 268 which is normally urged into central position by the two oppositely acting springs 269 and 270. The complementary member 271 has forklike 45 ends 272 that are secured to the block 268 and these ends preferably slide in interfitting relation with the part 266 to prevent lateral swinging of these parts. Shank 273 terminates in a ball 274 pivoted to a block 275 that, by means of a nut 276 (Fig. 10), 50 may be secured in the slot 277 of the gear-segment at any desired radial distance from its center 259. The shank 278 of the other member also terminates in a ball 279 that is received by a lug 280, projecting 55 laterally from the arm 260.

The nail feeder to be used in connection with this mechanism may be of a conventional type as to certain of its details, and it may take the form of a universal nail 60 block 281 (shown best in Figs. 2, 4, 7 and 8)

provided with a series of holes 282 selected ones of which are adapted to be filled with nails preparatory to the block being moved into registry with the holes in the regular nail guide or anvil 283. This nail block 281 is normally stationed at one side of the anvil, and is mounted to slide on the rails 283' (Fig. 7), so that it may be projected over the anvil. This nail block is reciprocated by the action of a lever F (Figs. 3 and 5) fulcrumed on the rod 262; the arm 284 of which carries a roller 285 riding in a cam groove Zf of the cam wheel Z. This groove, at proper intervals, oscillates the arm 284, thus producing a corresponding movement in the 70 companion arm 286 (Figs. 4 and 7), which extends upwardly through the lower deck 139 of the machine and terminates in the forked end, shown best by Fig. 4, which, by means of a resilient link 287, is connected 75 with the nail block 281. This resilient link comprises a guide rod 288 (Fig. 2) on which slides a block 289 that is pivoted to a yoke piece 290 which is in turn pivoted to the forked end of the lever 286. Opposing 80 springs shown by Fig. 2 keep these parts in normal relation, but permit of yield in case of undue resistance, thereby avoiding 85 breakage.

It is to be noted that this nail block reciprocates over the anvil 283, and fills the holes 291 thereof with nails while the above described fan is dispersed and is receiving blanks so that by the time the fan is closed up to bring the blanks in superimposed relation overlying the anvil 283, the nail 90 block will have been withdrawn.

Referring now to Fig. 8, there is shown a pin 292 that is in position to impact the pivoted bottom plate 245 of the first blade 105 of the fan and swing it out of the way into the position shown by Fig. 7 when the blade moves directly over the anvil 283. In like manner, the blade 241 carries a stop 293 (Fig. 8) that similarly impacts the bottom 110 plate 294 of the adjacent blade and swings it out of the way into the same position when this blade superposes the former, and so on throughout the series. In this way, all of the bottom plates are thrown to one side 115 as shown in Fig. 2 and all of the blades are brought into superimposed relation over the anvil, and the blanks may now be discharged into a heel pile and registered.

The releaser for the blanks in the fan consists of a wedge rod 295 (See Fig. 4) which slides in a bracket 296 depending from the upper deck 128. This wedge rod is forced down by the lever 297 which is pivoted at 298 to the standard 299, and has its end 120 300 entering the annular groove 163 of the common actuator 151'. A link 301 connects the wedge rod 295 with this lever, and at an appropriate moment this wedge rod 125 descends and enters the recess 250 in each 130

blade and spreads the prongs 242 and 243 sufficiently, so that the blanks may be received upon each other. They are now in a condition for being pressed by the means 5 to be described.

The blank pressing mechanism is shown in detail by Figs. 15 and 16 and it comprises a tubular plunger 302 which is adapted to slide longitudinally up and down in the 10 bracket 303 and its lower end member carries a pressure plate 304 that contacts directly with the uppermost blank and at the same time is adapted to clinch over the ends of the nails during the nailing operation. This 15 plate is made removable and interchangeable by being retained by the dove tail 305. This tubular plunger is actuated by means of a lever 306 (Figs. 2 and 4) which is pivoted at 307 on a shaft 308 which projects inwardly from the side frame member 309 (Fig. 4). The plunger engaging end of the lever 306 is forked, as indicated by 310 (Fig. 16) and is connected to the adjustable 20 collar 312 on the tubular plunger by means 25 of links 311. The lever 306 is in turn actuated from the camwheel Z (Fig. 5) by means of a lever G having a roller 313 riding in a cam groove Zg. This lever G is pivoted to the shaft 182 and has an arm 183" (Fig. 7) 30 projecting towards the machine (Fig. 2) and this arm is pivoted to the lower member 314 of a resilient link; the upper member 315 of which is pivoted at 316 to a lever 306' (dotted lines Fig. 2) fast to the hub 307 of the 35 lever 306. The construction of this resilient link is shown clearly by Figs. 2 and 4, in which the lower member 314 has a rod 317 entering the bore of the upper member and terminating in a shoulder 318. An expansile spring 319 serves to keep these members in contracted relation but provides the yield necessary to compensate for the varying 40 thicknesses in the blanks.

The blanks are pressed together at the 45 down-stroke of this plunger and are then ready for being nailed; but as the plunger is maintained against the blanks by spring pressure, it is necessary to provide a positive lock mechanism to prevent the plunger 50 from retreating under the pressures exerted on the heel pile by the nailing operation. This will now be described.

The plunger lock is in this instance in the nature of a silent ratchet and consists of 55 two rollers 320 and 321 (Fig. 15) which ride in the slots 322 in the frame portion 303 and which are brought to press against the sides of the tubular plunger by means of the inclined sides 323 of the casing, under the 60 action of the expansile springs 323, 324. By reason of the effect of these rollers, as will be readily understood, the tubular plunger is at all times free to move downwardly by spring action and yet may not retreat even 65 under a greatly increased counter pressure

until the rollers 320 and 321 are released. The nailing operation now takes place and the means for doing this will be described.

The nailer consists of a plunger shaft 325 slidable vertically in the bearing bracket 70 326 (Figs. 3, 13 and 14) which is fastened to the frame member 327 (Fig. 1). This plunger shaft 325 carries a head 328 to which is secured a nail driver plate 329 that is made interchangeable for the purpose of enabling different nail driver arrangements 75 to be conveniently utilized. Thus, the plate 329 provides holes 330 (Fig. 14) through which pass the shanks 331 of nail-drivers 80 which are retained in place by means of the heads 332 and which enter the appropriate apertures in the anvil or nailing plate 283, above described. These holes are occupied by nails delivered from the nail block 281 and when the nail drivers 331 rise, the nails 85 will be forced through the heel pile and will be clinched over the top blank by means of the clincher plate 304.

This nail driver mechanism is operated from the cam-wheel W by means of the 90 lever H (Figs. 3 and 5), which is pivoted at its hub 333 on the shaft 262 (Fig. 5) and its one arm 334 carries a roller 335 riding in a cam groove Wh (Fig. 5) and its other arm 336 extends downwardly and at its 95 lower end is pivoted to a link 337 (Fig. 3) which controls a toggle composed of the links 338 and 339. The link 339 is pivoted at 340 to the standard 341 and its upper end is pivoted at 342 to the lower end of the 100 link 338 which in turn is attached to the floating pivot 343 that is positioned by the link 344 that is pivoted to the frame at 345. The short links 346 connect this floating 105 pivot with the plunger rod 325 so that when the toggle is extended the latter is forced upwardly to drive the nails and it is withdrawn when the toggle is broken by the movement of the lever H.

The anvil depressor is for the purpose of 110 getting the anvil or nail block out of the way when the heel is finished so that the heel blank ejector may come into play and discharge it. This block 283 is arranged to slide vertically in the guides 347 (Fig. 13), 115 and it is maintained in its position by means of a toggle consisting of the upper link 348 and the lower link 349. The upper link is pivoted by the pin 350 to the anvil 283 and the lower link is pivoted by the pin 351 to 120 the stationary bracket 326 before described, and the upper link has a forked end 352 which by means of the pin 353 is pivoted to the lower link. This lower link preferably has a portion 354 bridging the bracket 326, 125 and extending integrally into connection with a similar link on the other side, thus providing a more rigid structure. This toggle is broken by means of a link 355 pivoted at 356 to the lower link of the toggle and at 130

357 to the end of the arm 358 (Fig. 3) forming a part of the lever I (Figs. 3 and 5) which rocks on the shaft 262, and has its other arm 359 provided with a roller 360 5 that rides in a cam groove W¹ on the cam disc W. In this way the toggle controlling the anvil is broken and extended; it being extended during the pressing and nailing operations, and it being broken for the purpose of ejecting the heel as will now be 10 described.

The heel ejector consists of a push rod 361 (Figs. 4, 15 and 16) which is forced downward through the hollow presser plate plunger 302, and compels the heel to follow the retreating anvil. This push rod is forced 15 down by means of a lever 362 pivoted at 363 to the bracket 364 (Fig. 2) and having its other end connected to an adjacent collar 20 365 fast to the push rod by means of links 366. This lever 362 has a second arm 362' (Figs. 2 and 4) which is in turn actuated by a resilient link 367, similar in construction to the link 315, that extends downwardly 25 through the lower deck 139 of the machine, and has its lower end connected to the arm 368 (Fig. 2) of the cam lever J (Fig. 5). This lever has its hub 369 pivoted to the shaft 182 (Fig. 5) and its other 30 arm 370 carries a roller 371 that rides in a cam groove Y¹ of the cam wheel Y. As the cam wheel Y rotates, this lever J will be oscillated and at an appropriate time will force down the push rod 361 to cause the 35 nail heel to follow the anvil as it descends after the nailing operations. To be delivered from the machine, this nailed heel requires to be ejected laterally and the means for so doing will now be detailed.

40 The lateral ejector for the heel consists of a pusher 372 (Figs. 7, 10 and 11) fastened to the end of a rack 373 sliding in bearings 374, in mesh with a gear-segment 375 that is pivoted to a post 376, depending from the 45 deck 139 and is normally maintained in the position shown in Fig. 10 by means of a suitably connected helical spring 377. When the lever 260 operates to spread the fan it also urges the collar 378 to the right (as 50 shown by Fig. 11) through the link 379. This collar carries a pivoted dog 380 (Fig. 12), the foot 381 of which enters a notch in the push rod 382 in which it is held by a spring 383 so that the push rod is advanced 55 with the lever 260, and this rod by means of the link 384 swings the gear-segment 375 clockwise and actuates the ejector 372 to discharge the heel. As the collar 378 continues forward the dog strikes a stop 385 60 secured to the underside of the deck 139 and this lifts the foot 381 out of the recess in the push rod 383, and the spring 377 then becomes effective to throw the ejector 372 and the gear-segment 375 into the normal 65 relation shown by Fig. 10.

The releaser for the blank presser 304 is for the purpose of getting this member out of the way so as to permit the fan blades to be again dispersed to receive another set of blanks. This mechanism is shown best 70 by Figs. 2, 15 and 16 and comprises a lever 386 (Fig. 16) having two fingers 387 that project through the slots 322 and terminate above the rollers 320 and 321. This lever is normally in the position shown by Fig. 16, 75 and it has an operating arm 388 which is adapted to be moved outwardly when the actuating rod 389 is depressed. This rod is guided by a slot 390 riding the pin 391 carried by the bracket 303, and it carries a cam 80 392 adapted to impact the arm 388 and swing it outwardly so as to depress the fingers 387 and release the rollers 320 and 321 from their frictional engagement, thus enabling the presser 304 to rise. This movement of the rod 389 is effected by means of the finger 393 (Fig. 2) on the presser operating lever 362 that hits the upper end of a stop 394 on said rod at the end of the downward movement of the lever and depresses 90 it. When the presser 304 rises, the lever 306 also rises, hits the lower end of the stop 394 and restores the normal position of the rod 389 preparatory to the next cycle of the machine. 95

The fan spreading means has been in part described; but certain features thereof should be further explained in connection with Fig. 8. When the finished heel has been forced down with the retreating anvil, 100 and after the blank presser 304 has been withdrawn, the blades constituting the fan are again spread out, so that each blade will take its proper position closely adjacent its magazine preparatory to receiving a blank 105 therefrom which has by this time been seized by the picker and dipped in the paste. This is done by the outward swing of the arm 251 from the position shown in Fig. 8. This arm carries directly with it the blade 110 256 to which it is secured by the pin 254 and this blade moves out a proper distance from its immediate companion; whereupon the pin 395 (Fig. 7) engages the end of the slot 115 in the blade connecting link 396 that is pivoted at 397 to the immediately underlying blade. In like manner, this underlying blade first swings away from its underlying companion for a small angular distance and then by means of a similar link 396, the 120 relative movement between the two is discontinued, and in this way the fan is spread out into a proper position.

Should it be desired to use a smaller number of blades those at the end of the extent 125 of swing of the arm 251 may be limited by the means of the adjusting nut 276, shown by Fig. 10.

In order to avoid an idle operation of the unused lift pickers when less than the num- 130

ber provided for the machine are in use, that is, when a heel having a less number of lifts than the whole number of magazines is to be built, means is provided for disconnecting 5 the unused pickers from their actuators. Referring to Fig. 2 it is seen that the ball shaped end 164 of the walking beam R is carried by an adjustable end piece 400, which, in loosening the bolt which clamps 10 it to the beam R may be slid, within the slot 401 formed for its reception, outwardly, away from the common actuator 151'. Similarly, on loosening the set screw 402, the block 403, by means of which the link 130 15 is secured to the common actuator 131, may be slipped off of said actuator. After this latter disconnection the block 403 may conveniently be moved to the right (Fig. 2) and latched to the bell crank in any suitable manner, to keep it from being engaged by the moving actuator. Thus all the pickers not in use may be rendered ineffective to perform their functions.

Wherever the terms "blank" or "lift" are 25 used to designate the layers of the heel pile produced by the machine, these terms are used in an inclusive sense as defining any blank capable of being utilized in building heels, irrespective of the particular shape 30 which they may have when they are first collected in the form of a heel pile.

Without further elaboration, the foregoing will so fully disclose the gist of the invention that others will be enabled by applying 35 current knowledge readily to adapt it for various purposes without, however, omitting certain features that, from the standpoint of the prior art, fairly constitute essential characteristics of its generic or 40 specific aspects, and therefore such adaptations should and are intended to be comprehended within the meaning and range of equivalency of the following claims.

Having thus described the invention, I 45 claim as new and desire to secure by Letters Patent:

1. A machine for making heels having, in combination, a series of magazines adapted to hold lifts piled in stack formation, 50 means for producing a series of lifts from said magazines and depositing them in a dispersed relation adjacent said magazines, and means for collecting said dispersed lifts into a stack.

55 2. A machine for making heels having, in combination, means for collecting a row of lifts into a stack, a row of lift magazines adjacent said collecting means, and means for simultaneously transferring a lift from each magazine in the row to the control of said collecting means whereby to form a heel pile.

60 3. A mechanism of the nature revealed combining a plurality of magazines; each 65 adapted to hold a number of blanks; means

for simultaneously yielding from all of said magazines a number of blanks; and subsequently acting means for bringing the yields from the several magazines into a predetermined serial relation and flatwise registry. 70

4. A device for stacking heel-blanks comprising a battery of magazines providing a number of delivery apertures located approximately in the same plane; ejector mechanism for simultaneously projecting 75 blanks through said apertures; and means for shifting the blanks from their plane into superimposed registry in a single heel pile.

5. An apparatus for facilitating the stacking of blanks to form a laminated heel 80 comprising a plurality of magazines; means for simultaneously obtaining from a plurality of said magazines a number of blanks; means for arranging said blanks in superimposed registry; and means for pressing 85 the stack of registering blanks.

6. A mechanism of the nature disclosed, combining a guide for a stack of blanks; a propeller operating intermittently at one end of the stack to feed the same; means for 90 successively removing blanks one by one from the other end of the stack; and clamping devices for periodically frictionally engaging the edges of the blanks at the last mentioned end of said stack. 95

7. A mechanism of the nature disclosed combining a magazine adapted to contain a stack of blanks; means for feeding a stack of blanks and operative at one end thereof; mechanism for determining the rate of feed 100 and controlled by the blanks at the other end of the stack; means for removing blanks from said last mentioned end; and a stack gripping instrumentality operative on said blanks at said last mentioned end. 105

8. A mechanism of the nature disclosed combining a blank supply; means for individually seizing blanks from said supply; and mechanism for withdrawing said means with its seized blanks; and an independently acting mechanism adapted to shift the position of said withdrawn means. 110

9. A mechanism of the nature disclosed combining a magazine adapted to contain a stack of blanks; a picker for seizing individual blanks; a head for withdrawing said picker with its seized blank in a direction transverse to the plane of the blank; and a locator for shifting the position of the picker in a direction substantially parallel with the plane of the blank. 115

10. A mechanism of the nature disclosed combining a magazine for a stack of blanks; means for feeding the stack of blanks within the magazine; a picker for seizing the 120 end blank; a head for withdrawing said picker with its blank; a locator for shifting said withdrawn picker laterally; means for supplying adhesive material to said blank in its shifted position; mechanism op- 125

erative during the shift of said picker to control the feed of the blanks; and an instrumentality for receiving the blank from said picker.

- 5 11. A mechanism of the nature disclosed combining a plurality of flat blades each having a blank receiving opening and each providing means for frictionally gripping the edges of the blank; a platform constituting a bottom for each of said openings when said blades are in blank-receiving position; and means for moving said blade to bring said openings into registry and for effecting a relative movement between each of 10 15 said blades and its platform, whereby said openings may be bottomless when in registry.

12. A mechanism of the nature disclosed combining a plurality of members, each having a blank receiving seat, said members being movable to bring said seats either in overlying registry or in dispersed relation; mechanism for placing a blank in the seat of each of said members when in dispersed relation; means subsequently operative to 20 25 move said members to bring said seats into registering relation; and means for pressing said blanks together stack like.

13. A mechanism of the nature disclosed combining a plurality of members each having a blank-receiving seat; an anvil; means for moving said members to bring the seats thereof from a dispersed blank-receiving relation into superimposed registry with said anvil; and means for pressing the 30 35 blanks superimposed in said seats against said anvil.

14. A mechanism of the nature disclosed combining a plurality of blank-receiving members, said members being movable to bring them either in overlying registry or in dispersed relation; mechanism for delivering a blank to each of said members when in dispersed relation; means subsequently operative to move said members to bring 40 45 said blanks into registering relation; and means for removing said blanks together while arranged stack like.

15. A mechanism of the nature disclosed combining a plurality of members, each having a blank receiving seat; an anvil; means for moving said members to bring the seats thereof from a dispersed blank-receiving relation into a blank-superimposed relation with said anvil; and nailing mechanism at 50 55 said anvil operative to nail said blanks together stack-like.

16. A mechanism of the nature disclosed combining a supporting anvil; automatic means for stacking a plurality of individual, 60 separated blanks thereon; a pressure member adapted to press said blanks against said anvil; and nailing mechanism operative automatically to drive a nail or nails through said pressed stack of blanks.

- 65 17. A mechanism of the nature disclosed

combining an anvil member; mechanism for automatically stacking a series of adhesively coated blanks on said anvil; a pressure member adapted to advance to press said stack of blanks together against said anvil member; and means operative through one of said members to dislodge the stack therefrom when said members are moved apart to release the stack of blanks.

70 18. A mechanism of the nature disclosed combining a pair of pressure members, each movable towards and away from an intervening point; a blank-assembling mechanism adapted to carry a series of blanks into intervening relation with said members; means for causing said members to approach when said blanks are in said intervening relation to press the same and means for separating said members to permit the withdrawal of said mechanism past said intervening point.

80 85 19. A mechanism of the nature disclosed combining a series of elements each having a blank receiving seat and arranged in superimposed relation; a mechanism for operating said means to register said seats and bring said blanks together stack-like; an anvil; a pressure member arranged in opposition thereto; means for moving said pressure-member towards said anvil to press the blanks together and thereagainst; means for withdrawing said pressure member and also withdrawing said anvil; and an ejector operative to displace said stack of blanks with relation to the same.

90 95 100 105 20. A mechanism of the nature disclosed combining a supporting-member; means for superimposing a series of blanks on said supporting-member; a pressure member urged by spring-action against said blanks to press the same; a locking mechanism co-operating with said pressure-member positively to prevent retreat of the same; means acting in opposition to said locking mechanism to drive nails through said blanks; and means for rendering said lock inoperative to enable said pressure-member to be withdrawn.

110 115 120 21. A mechanism of the nature disclosed combining a plurality of members each having a blank-receiving seat and each having a relatively movable platform adapted to receive a blank and position it in said seat; and means for moving said members to bring said seats into superimposed relation and effect a lateral displacement of said platforms to enable said blanks to be directly contacted together flatwise.

125 22. A mechanism of the nature disclosed combining a relatively thin blade having a bifurcated end providing resilient prongs; means for springing said prongs apart, whereby a flat blank may be inserted flatwise therebetween; and means for withdrawing said first-mentioned means to enable said prongs to spring against the edges of said blank and to frictionally retain the same.

23. A machine for promoting the manufacture of heels composed of a predetermined number of superimposed blanks; said machine combining a series of magazines not less in number than the blanks composing the heel and each adapted to retain a stack of blanks; and means for simultaneously procuring a number of blanks, sufficient to form a single heel, from any predetermined number of said magazines while each magazine of the entire number retains its quota of stacked blanks.
24. A machine for facilitating the assembling of the blanks composing an unfinished heel and including in combination a predetermined number of magazines each adapted to hold a pile of blanks; and adjustable mechanism adapted simultaneously to procure from a selected number or the entire number of said magazines the full complement of blanks requisite to constitute a single heel.
25. A mechanism of the nature revealed combining a plurality of magazines adapted to hold, each a pile of similar blanks; means for simultaneously procuring from said magazines a number of blanks; and subsequently acting means for pressing the yields from the several magazines together flatwise in the form of a stack-like unit.
26. A device for stacking heel blanks comprising a battery of magazines providing a number of delivery apertures located in approximately the same plane: mechanism for simultaneously procuring blanks through said apertures; means for shifting the blanks from their plane into superimposed registry; and means for pressing said registered blanks together.
27. An apparatus for facilitating the stacking of blanks to form a heel comprising a set of magazines; means for simultaneously obtaining from a plurality of said magazines a number of blanks; means for applying adhesive to each of said blanks; means for arranging said blanks in superimposed registry; and means for pressing the stack of registered blanks.
28. A mechanism of the nature disclosed, combining a guide for a stack of blanks; an intermittently acting propeller operating at one end of the stack to feed the same; means for successively removing blanks one by one from the other end of the stack; and clamping devices for frictionally binding the edges of the blanks at the last-mentioned end of said stack at the time of impact between said means and said blanks to prevent displacement of the latter while said means is taking hold of said blanks.
29. A machine of the nature disclosed combining a magazine adapted to contain a stack of blanks; means for feeding a stack of blanks and operative at one end thereof: mechanism for determining the rate of feed and controlled by the blanks at the other end of the stack; means for removing blanks from said last mentioned end; and an automatic stop instrumentality operative to discontinue the action of the machine when the number of blanks in one of said magazines is reduced to a predetermined minimum.
30. A mechanism of the nature disclosed combining a blank supply; means for individually seizing blanks from said supply; mechanism for withdrawing said means with its seized blanks; an independently acting mechanism adapted to shift the position of said withdrawn means, and a stacking mechanism adapted to receive the blanks while in dispersed relation and bring them into stack-like relation.
31. A mechanism of the nature disclosed combining a magazine adapted to contain a stack of blanks; a picker for seizing individual blanks; a head for withdrawing said picker with its seized blank; means for moving said head first in a direction transverse to the plane of the blank and then in a direction parallel to said plane; and a mechanism for receiving the blank from said picker.
32. A mechanism of the nature disclosed combining a magazine for a stack of blanks; a picker for seizing the end blank; means for withdrawing said picker with its seized blank; means for applying adhesive material to said withdrawn blank; and an instrumentality for receiving the blank from said picker constructed and arranged to hold the blank in a definite position.
33. A mechanism of the nature disclosed combining a plurality of blades each having a blank receiving seat and adapted to be brought into a dispersed blank receiving relation; and means for moving said blades to bring said seats into over-lying relation.
34. A mechanism of the nature disclosed combining a plurality of members, each having a blank receiving seat, said members being movable to bring said seats either in overlying registry or in dispersed relation; means to move said members to bring said seats from a dispersed relation into registering relation; and means for bringing said blanks together stack-like.
35. A mechanism of the nature disclosed combining a plurality of members, each providing blank retaining prongs; an anvil; means for laterally moving said members to bring the prongs thereof from a dispersed blank-receiving relation into a superimposed registry with said anvil; and a plunger moving transversely to the direction of movement of said members for pressing the blanks retained by said prongs against said anvil.
36. A mechanism of the nature disclosed combining a plurality of members, each having blank retaining prongs and said mem-

bers being movable to bring said prongs either in overlying registry or in dispersed relation; mechanism for spreading said prongs and placing a blank therebetween 5 when said members are in dispersed relation; means subsequently operative to move said members to bring said seats into registering relation; and means for moving said blanks free from said prongs and for pressing said 10 blanks together stacklike.

37. A mechanism of the nature disclosed combining a plurality of members, each having a blank receiving seat; a corresponding plurality of magazines; means for simultaneously obtaining blanks from said magazines and placing them in the seats of said members; an anvil; means for moving said members to bring the seats thereof from a dispersed blank-receiving relation into a 20 blank-superimposed relation with said anvil; and nailing mechanism at said anvil operative to nail said blanks together stack-like.

38. A mechanism of the nature disclosed combining a supporting anvil; a plurality of 25 magazines arranged in dispersed relation; automatic means for obtaining a blank simultaneously from each of said magazines and for stacking said blanks on said anvil; a pressure member adapted to press said 30 blanks against said anvil; and nailing mechanism operative automatically to drive nails through said compressed stack of blanks.

39. A mechanism of the nature disclosed combining a plurality of magazines arranged 35 in dispersed relation; means for obtaining a corresponding number of blanks simultaneously from each of said magazines and for adhesively coating the same; an anvil member; mechanism for automatically stacking 40 the series of adhesively coated blanks on said anvil; a pressure member adapted to advance to press said stack of blanks together against said anvil member; and means operative through one of said members to dislodge the 45 stack therefrom when said members are apart to release the stack of blanks.

40. A mechanism of the nature disclosed combining a pair of pressure members, each movable towards and away from an intervening 50 vening point; a series of magazines; a blank assembling mechanism adapted to obtain a series of blanks simultaneously from each of said magazines and carry them into intervening relation with said members; means 55 for causing said members to approach when said blanks are in said intervening relation to press the same; and means for separating said members to permit the withdrawal of said mechanism from said intervening point.

60 41. A mechanism of the nature disclosed combining a plurality of magazines; a series of elements each having a blank receiving seat and each arranged in a different plane; means for obtaining a blank simultaneously 65 from each magazine; a mechanism for oper-

ating said means to register said seats and bring said blanks together stacklike; an anvil; a pressure-member arranged in opposition thereto; means for moving said pressure-member towards said anvil to press the blanks together and thereagainst; means for withdrawing said pressure member and also withdrawing said anvil; and an ejector operative to displace said stack of blanks with relation to the same. 75

42. A mechanism of the nature disclosed combining a supporting-member; a plurality of magazines; means for obtaining a blank simultaneously from each of said magazines; means for superimposing said blanks on said supporting-member; a pressure-member urged by spring-action against said blanks to press the same; a locking mechanism co-operating with said pressure-member positively to prevent retreat of the same, 80 means acting in opposition to said locking-mechanism to drive nails through said blanks; and means for rendering said locking-mechanism inoperative to enable said pressure-member to be withdrawn. 90

43. A mechanism of the nature disclosed combining a plurality of magazines each adapted to contain a stack of blanks; means for obtaining simultaneously from each of said magazines a predetermined number of blanks; a plurality of members each having a blank-receiving seat and each having a relatively movable platform adapted to receive a blank and position it in said seat; and means for moving said members to bring 100 said seats into superimposed relation and effect a lateral displacement of said platforms to enable said blanks to be directly contacted together flatwise. 95

44. A mechanism of the nature disclosed combining a relatively thin blade having a bifurcated end providing resilient prongs; means for springing said prongs apart, whereby a flat blank may be inserted flatwise therebetween; means for withdrawing said 105 first-mentioned means to enable said prongs to spring against the edges of said blank and to frictionally retain the same; means for shifting the position of said blade and means for removing the blank from between said 110 prongs when said blade is in its shifted position.

45. A machine for making heels having, in combination, two or more normally separated arms each having a blank-receiving 120 seat at one end and arranged in different planes, means for moving said arms in their respective planes to bring said seats in superimposed relation, means for depositing a blank in each seat while the arms are 125 separated, and means for nailing the blanks together after the seats have been superimposed.

46. A machine for making heels having, in combination, a plurality of normally sep- 130

arated arms arranged in different planes and each pivoted at one end at a common center, a blank-receiving seat at the free end of each arm, means for depositing a blank in each arm, and means for collapsing the arms fan-wise to bring the blanks carried thereby into superimposed relation.

47. A machine for making heels having, in combination, a row of circularly arranged lift magazines, and means including mechanism disposed within the circularly arranged magazines movable about the center thereof for removing a lift from each magazine and collecting said lifts in superposed relation to form a heel pile.

48. A machine for making heels having, in combination, a plurality of movable blank carriers, means for loading each carrier with a blank, means for moving the carriers to bring all the blanks into registry at a common point, means for releasing the blanks from the carriers in the form of a heel pile, and means for securing the blanks together.

49. A machine for making heels having, in combination, a series of magazines each adapted to contain a stack of blanks, means for picking a blank from each magazine and superimposing them flat-wise to form a heel pile, means for pasting the blanks picked from the magazines, and means for nailing the heel pile.

50. A machine for making heels having, in combination, a series of magazines in a line each adapted to contain a stack of blanks, means for simultaneously picking a blank from each magazine, a paste trough adjacent the magazines, means for dipping the blanks picked from the magazines in the paste trough, and means for bringing said blanks into registry flat-wise.

51. A machine for making heels having, in combination, a plurality of lift magazines, means for producing a series of lifts from said magazines and depositing them in a row, and means acting in a direction different from that of said producing means for collecting the row of deposited lifts in superposed relation to form a heel pile.

52. A machine for making heels having, in combination, assembling means for collecting blanks into a heel-body adapted to receive a sufficient number of blanks to constitute a single heel-body, means to operate said assembling means, a series of magazines adapted to hold blanks in stack formation adjacent to said assembling means, and means for simultaneously delivering to said assembling means said number of blanks one from each magazine.

53. A machine for making heels having, in combination, a row of magazines adapted to hold stacks of lifts, and means for producing a lift from each of said magazines, pasting said lifts, delivering them in a row

parallel to the row of magazines, and piling them in superposed relation at a common point.

54. A machine for making heels having, in combination, a series of magazines adapted to hold blanks piled in stack formation, means for simultaneously procuring a blank from one end of each magazine, said blanks corresponding in number to the component lifts of the heels to be built, and delivering them at an assembling station adjacent to said magazines, a paste trough adjacent said magazine ends, and means for applying paste from the trough to the blanks during their travel from the magazines to said assembling station.

55. A machine for making heels having, in combination, lift collecting means movable to advance lifts deposited thereon into flatwise registry, means for containing a supply of lifts, devices for producing from said last named means a series of lifts and depositing them in a row on the collecting means, and means for thereafter actuating said collecting means to assemble the lifts in the form of a heel-pile.

56. A machine for making heels having, in combination, a support to receive a row of lifts, means for periodically moving said support in the direction of the row to facilitate collecting the row of lifts in a pile, and means acting during the periods of rest of said support for depositing rows of lifts thereon.

57. In a heel-making machine, a row of supports for holding a series of heel-lifts in correspondingly disposed positions, said supports being movable in the line of said row to collect the lifts supported thereon, in a pile.

58. In a heel-making machine, a row of supports for holding a series of heel-lifts in correspondingly disposed positions, said supports being movable one over the other, in the line of said row, to move each lift on to the next succeeding lift in their order of arrangement.

59. In a heel-making machine, a holder having a series of compartments each arranged to receive a stack of lifts, a corresponding series of lift-supports arranged adjacent thereto, a separating device movable to deliver a lift from each stack on to the support corresponding thereto, and means to collect the lifts held on said supports, in a pile.

60. In a heel-making machine, a series of horizontally disposed lift-supports, arranged in a row, at elevations which are successively lower by a distance not less than the thickness of the lifts, means to deliver a lift to each of said supports simultaneously, and means, movable in the direction of said row, to slide the lifts one over the other and collect them in a pile.

61. In a heel-making machine, a series of horizontally disposed lift-supports, arranged in a row, at elevations which are successively lower by a distance not less than the thickness of the lifts, means, movable in the direction of said row to slide the lifts held at higher elevations on to the lifts held at lower elevations, successively, and a heel-holder at the end of said row arranged 10 to receive the assembled lifts from the supports of lowest elevation.

62. A machine for making heels having, in combination, a plurality of lift magazines, means for producing a series of lifts 15 corresponding in number to the component lifts of the heels to be built, one from each magazine, and while retaining control thereof depositing them in definite positions in a row, and means operating in the direction 20 of said row for moving said lifts from their positions of deposit.

63. A machine for making heels having, in combination, a series of lift magazines, means for periodically producing a series 25 of lifts, one from each magazine, and while retaining control thereof depositing them in definite positions in a row, and means acting during the intervals between the successive productions of lifts from the magazines 30 for moving all the deposited lifts beyond the series of magazines in a direction corresponding to that of the row.

64. A machine for making heels having, in combination, means for producing a series 35 of lifts corresponding in number to the component lifts of the heels to be built and, while retaining control thereof, depositing them in definite positions in a row, and means operating in the direction of said row 40 for moving said lifts from their positions of deposit.

65. A machine for making heels having, in combination, means for producing a series 45 of lifts and depositing them in a row, and mechanism including movable means upon which the series of lifts are deposited for collecting said lifts in superposed relation to form a heel pile.

66. In a machine for making heels, a row 50 of magazines adapted to hold lifts piled in stack formation; a row of lift-receiving seats, so related to each other as to hold the lifts in parallel planes, arranged adjacent said magazines; and means for simultaneously delivering a series of lifts from 55 said magazines, one lift upon each of said seats, whereby a collection of the lifts in a stack is facilitated.

67. In a machine for making heels, a row 60 of magazines adapted to hold lifts piled in stack formation; means adjacent said magazines for supporting lifts in position to be assembled, said means being constructed and arranged to support a row of lifts with each 65 lift lying in a different plane; means for

simultaneously procuring a series of lifts from said magazines, and delivering the series to said supporting means; and means for supplying paste to said lifts.

68. A machine for making heels having, 70 in combination, a magazine for a stack of lifts, a picker for seizing the end lift, a head for withdrawing the picker with its lift, a paste trough, a lift receiving member, and means for shifting said head to bring 75 the picker first to the paste trough and then to a position for depositing the lift on said receiving member.

69. A heel making machine having, in combination, means for producing a series 80 of pasted lifts in a row, an anvil, means for stacking said lifts thereon, a pressure member opposite the anvil, and means for operating said member to press the lifts together.

70. A heel making machine having, in combination, means for producing a series of lifts in a row, an anvil, means for stacking said lifts thereon, a pressure member adapted to press said lifts against the anvil, 90 and means for fastening the lifts together while under pressure.

71. A heel making machine having, in combination, means for producing a series of lifts in a row, an anvil, means for stacking said lifts thereon, a pressure member at one side of the anvil, a nail driver at the other side of the anvil, and means for pressing the stack of lifts and then actuating said nail driver.

72. A heel making machine having, in combination, a pair of pressure members at least one of which is movable relatively to the other, a lift assembling mechanism adapted to deliver a series of lifts into flat- 105 wise registry in an intervening relation with said members, means for operating said movable member to press said series of lifts together, and means operating through the other member for fastening said lifts together while under pressure.

73. A machine for making heels having, in combination, a series of lift magazines each having a lift delivery aperture, means for procuring a series of lifts from said 115 apertures and retaining them temporarily in a row adjacent the magazines, means for shifting the lifts in the line of said row into superposed registry, and means for pressing said registered lifts together.

74. A machine for making heels having, in combination, a series of lift magazines each having a lift delivery aperture, means for simultaneously procuring lifts from said 125 apertures, delivering them to positions adjacent their respective magazines and then arranging them in superposed registry, and means for securing said registered lifts together.

75. A machine for making heels having, 130

in combination, a series of lift magazines, means for ejecting the end lift from each magazine and pasting said lifts, and means adjacent the magazines for receiving the ejected lifts constructed and arranged to hold said lifts temporarily in a row and then move them past the magazines.

76. A machine for making heels having, in combination, a series of lift magazines, 10 means for simultaneously ejecting a lift from each magazine and pasting said lifts, and means for receiving the ejected lifts constructed and arranged to maintain said lifts in a row with each lift in a definite position with relation to the others.

77. In a machine for making heels, a plurality of members each having a lift-receiving seat, said members being movable to bring said seats either in overlying registry 20 or in dispersed relation, and means for moving said members to bring the seats thereof into either relation.

78. A machine for making heels having, in combination, a plurality of magazines, a 25 plurality of members adjacent said magazines adapted to retain a series of lifts in a row, means for delivering a series of lifts from said magazines to the control of said members, a support on which the lifts are to be stacked, and means for moving said members to deliver said lifts onto said support in stacked relation.

79. A heel building apparatus, comprising a support having a series of surfaces ar- 35 ranged in steps, a series of separate magazines each adapted to contain heel lifts superposed in a pile, and means for transferring lifts from the several magazines to the several surfaces of said support.

40 80. An apparatus for use in the building

of heels, comprising means for simultaneously applying adhesive to a number of lifts, a lift-holder having a series of lift-engaging portions in stepped relation to one another, and means for placing the lifts in engagement respectively with the several lift-engaging elements of said holder.

81. An apparatus for building heels, comprising a support having a series of discontinuous surfaces arranged in approximately 50 parallel planes, feeding means adapted to move a number of lifts simultaneously into engagement each with one of said surfaces, and means for applying adhesive simultaneously to certain of said lifts.

82. An apparatus for use in the building of heels by the within described method comprising a support having a series of stepped surfaces to receive heel lifts, a series 60 of separate upright magazines for heel lifts each opposite to one of said stepped surfaces and adapted to hold lifts in a pile, and means for transferring lifts from the several magazines simultaneously to said stepped surfaces.

83. A heel building apparatus comprising in combination a series of magazines for heel lifts, means for ejecting lifts substantially at the same time from a number of said magazines, cement-applying means opposite said magazines into contact with which the lifts are brought by the ejecting means, and a support to which said lifts pass from said cement-applying means, said support having lift-receiving portions which 70 occupy a stepped relation to one another.
